UNITED STATES PATENT OFFICE.

HENRY H. KNIPE, OF OLNEY, ILLINOIS.

MESSAGE-METER DEVICE.

1,348,499.

Specification of Letters Patent. Patented Aug. 3, 1920.

Application filed August 28, 1919. Serial No. 320,512.

To all whom it may concern:

Be it known that I, HENRY H. KNIPE, a citizen of the United States, residing at Olney, in the county of Richland and State 5 of Illinois, have invented a new and useful Message-Meter Device, of which the following is a specification.

The object of my invention is to provide an improved device adapted to enable telephone operators to more conveniently make and keep their record of toll business, and at the same time to provide a device which is not too expensive for small exchanges. It is further my object to provide a device 15 of such shape and size that it can be placed between two operators' positions on most magneto or common battery boards and which can be conveniently placed with brackets even with the operators' keys on the end of the board. I attain the objects 20 of my invention by the device illustrated in the accompanying drawings, in which—

Figure 1 is a perspective view of the device ready for use;

25 Fig. 2 is a rear elevation;
Fig. 3 is a side elevation; and
Fig. 4 is a top plan.

Like numerals designate like parts in each of the views.

30 Referring to the accompanying drawings I provide a suitable narrow base plate 1 of sufficient width to accommodate an especially tabulated pad 11 on which the record of message is entered. I provide a raised 35 portion or platform 2 at one end of plate 1, on which is formed the upstanding plate portions 3 and 5, which with spring 4 provide a support for the timing device 16. Mounted on platform 2, as shown in Fig. 40 2, I provide a bar 7 on which an operating lever 6 is affixed at one end. Bar 7 is provided with L-shaped fingers 9 adapted to engage and hold the tab 11. I provide a spring 8 attached to bar 7 and platform 2 45 and arranged to resiliently press fingers 9 onto pad 11, subject to their release by depressing lever 6.

Mounted at one side of platform 2 I provide a suitable counter 12 adapted to be manually operated by the operator depressing the finger lever 13 to register a message. Counter 12 may be provided with a suitable resetting wheel 14. On the other side of platform 2 I provide a dating pad 15 positioned within the platform as illustrated 50 in the drawings and adapted to hold a dating stamp (of ordinary construction and not shown).

Base plate 1 is provided with suitable openings 17 for securing it firmly to the 60 table on which the device is placed when it is desired to fasten it in one place.

The message meter device has nothing about it that is expensive to maintain. The one wearing part is the timing device 16. 65 The counter is operated manually by the operator who numbers each toll ticket on the pad 11 and keeps a complete record of calls, each ticket being dated for the particular day by the pad and dater which is 70 held by the device 15.

What I claim is:

1. As a new article of manufacture, a metal holder of the type described comprising a narrow base plate suitable for holding a pad, a raised platform at one end of the plate, upstanding plate portions at the rear of the raised platform said portions being shaped to receive a clock, and a spring secured to the rear of the aforesaid platform and releasably holding the clock in place. 75

2. In combination with the metal holder described in claim 1, L-shaped fingers projecting through the platform and adapted to releasably engage and hold a pad on the plate, a bar rotatably mounted on the platform to which the L-shaped fingers are attached, a spring attached at one end to the bar and at the other end to the platform 85 to normally rotate the bar and compress the L-shaped fingers downward, and an operating lever attached to one end of the bar. 90

HENRY H. KNIPE.
